Claims priority, application Germany Oct. 16, 1959

3 Claims. (Cl. 102—78)

The invention relates to time fuzes with sensitive percussion fuzing for projectiles, with and without rifling. It is an object of the invention to equip such a fuze with safety devices which are reliable in transport and also as regards timing. The invention is characterised by a cylindrical worm which is rotatably mounted on the striker pin and which is driven by an inertia weight which is non-rotatably guided in the fuze housing and is provided with transverse pins engaging in the worm groove, the said inertia weight carrying an axially parallel locking member which secures the balance-type regulator of a timing mechanism. In the preferred embodiment of the invention, a toothed wheel is arranged on the cylindrical worm so as to rotate therewith, the said wheel driving a balance or escapement wheel which co-operates with a rocking pallet which is mounted at the forward end of the worm. For further locking effect, a known rocker plate which closes the striker pin passage can be mounted behind the worm, the said rocker plate being held against the action of its torsion spring in the "safe" closed position by a stop pin, which bears externally against the hollow end of the worm, the wall of the hollow end also being formed with a recess for the passage of the stop pin on the rocker plate in the rear dead-centre position of the inertia weight when the worm has completed its rotation.

The allotment of a double safety function to the safety timing mechanism and a construction of its gearing with a cylindrical worm element contributes to a compact, simple and reliable construction.

Other features and advantages of the invention will be apparent from the following description of one constructional example, and from the drawing and claims.

In the drawing:

FIG. 1 is a longitudinal section of the fuze, including its housing;

FIG. 2 is a longitudinal section of the timing mechanism and of the safety time mechanism, shown to a larger scale as compared with FIG. 1;

FIG. 3 is a sectional view on the line 3—3 of FIG. 2;

FIG. 4 is a sectional view on the line 4—4 of FIG. 2;

FIG. 5 is a sectional view on the line 5—5 of FIG. 2 with the blocking plate of the striker pin passage in the "safe" position;

FIG. 6 is a section corresponding to FIG. 5, but with the blocking plate of the striker pin passage in the end "safe" position.

In order that the sensitive fuzing and also the time fuzing of the fuze illustrated may be made safe, there is provided a time safety mechanism which adjoins the bottom plate 58 of the timing mechanism (FIG. 2). The reference 100 represents the top plate of the time-safety mechanism, 101 is an intermediate plate, 102 is a cover plate, while 103 is an additional intermediate plate and 104 is the bottom plate. Some of these mechanism plates are held assembled by screws and some are held in spaced relation by posts 105, 106. Rotatably mounted between the plates 101 and 102 is the cylindrical worm member 107; it comprises a worm thread 107a which has a steep pitch and which is engaged by a pin 108 fixed radially in an inertia weight 109. The latter is guided axially on the posts 105 and 106 (FIGS. 2 and 4). The toothed wheel 110 is rotatably mounted near the forward end of the

2

worn element 107 and it meshes, as shown in FIG. 1, with the pinion 111 of an escapement wheel 112 which co-operates with the rocking pallet 113, which is pivotally mounted on the striker pin stem 15b as a pivot. The coiled spring 119 is fitted with pretension between the inertia weight 109 and the cover plate 102. Fitted into the weight 109 parallel to the fuze axis is the locking finger 114, which extends through suitable holes in the plates 101, 100, 58, 57, 56, 55, 54, 53 and 52 and has the object to secure the balance-type regulator 68 of the timing mechanism until the predetermined time-safety travel has been completed and above all also to make it safe against the action of shocks during transport. The forward end of the safety finger 114 is reduced at 114a to a smaller diameter, as shown in FIG. 1, so that by means of a hairpin spring 115 pretensioned for expansion and fitted between the plates 58 and 100, the safety locking finger 114 and with it the inertia weight 109 are held in the (rear) armed position when the time-safety mechanism has completed its service as a safety device. The purpose and function of the timing mechanism 68 is to provide for a balance regulation and it operates in such a way that the regulator 68 is locked until firing takes place by a locking projection projecting into its range of oscillation, as shown immediately to the right of the element 68.

The stem of the safety finger 114 is made sufficiently long, as is also the length of travel for the inertia weight 109 and the timing for the delay mechanism (107a/103/110/111/112/113), that with brief shocks during transport, the reduced part 114a of the safety finger 114 still does not come into the range of the locking spring 115, but in fact the inertia weight and with it the safety finger 114 again return to the initial locking position after the shock has subsided. The balance mechanism of the timing mechanism thus remains locked, so that the said mechanism cannot be started as a result of a shock during transport. Furthermore, the safety arrangement still to be described for the blocking plate on the worm member 107 for the needle passage is so arranged that it is still not released by a brief rotation of the worm member 107 caused by a shock during transport. The time-safety mechanism is in other words adapted to the ballistic property of the rocket projectile, that is to say, to the low firing pressure and to the fact that the maximum acceleration is only reached after about 0.5 to 0.8 second. The arming of the timing mechanism must take place in a reliable manner, but on the other hand the fuze must be safe during transport and on firing. The running period of the time-safety mechanism is arranged accordingly.

In the example illustrated, the cylindrical worm member 107 completes approximately three quarters of a revolution from the starting position at the front to the end position, which is the armed position.

The cylindrical worm element 107 is reduced at its rear end at 107b to a smaller diameter and is guided with the said extension piece in the cover plate 102, which simultaneously serves as an axial bearing therefor. The worm element 107 is drilled axially at 107c, so that a collar 107b is formed, which is cut away at 107d, as shown in FIGS. 2, 5 and 6, so that a safety pin 116, which is arranged on the blocking plate 117 for the needle passage and bears during the "safe" period against the collar 107b (FIG. 5) but is allowed to pass during the safe period (FIG. 6) when the inertia weight 109 has reached its rearward position (resting on the cover plate 102), whereby the safety finger 114 is locked at 114a with the hairpin spring 115 and the worm element 107 has reached the armed position in which the cut-away part 107d of the collar 107b lies in the range of movement of the safety pin 116. Acting on the blocking plate 117 is the spring 118 which is installed with pretension and

which tends to rotate the plate 117 in a clockwise direction, as indicated in FIGS. 5 and 6. In order to avoid the pointed end of the striker pin section 15b resting on the said member 117 and obstructing the operation thereof, a compression spring 119 is fitted with suitable pretension in the hollow shaft 16 of the spring barrel, the said spring 119 engaging on the rear face of the enlargement 15a of the striker pin.

The operation of the fuze will now be described:

Safety during transport.—Should the fuze or the projectile provided with the fuze drop on to its nose during handling, the striker pin 15 will certainly be driven inwardly by the plate 16 with destruction of the diaphragm 17; the pointed end of the said pin, however, strikes against the blocking plate 117 for the striker pin passage, the said plate being in the safe position (FIG. 5). Since the forces of inertia operative in this case are unidirectional with the force of the thrust spring 119 behind the inertia weight 109, no movement of these parts occurs in practice.

On the other hand, should the projectile drop on to its base, only comparatively small mass forces act on the striker pin, and these are damped by the spring 119 and generally do not lead to any damage because of upsetting of the striker pin 15b on the blocking plate 117.

However, when the projectile is dropped in this direction, mass forces are operative on the inertial weight 109, which can cause the weight to slide back a small distance relatively to the spring 119 and initiate the movement for a brief instant of time of the worm element 107, toothed wheel 110, pinion 111, regulator wheel 112 and the rocking pallet 113. However, the parts are of such dimensions that an impact due to dropping is not in any way operative for such a length of time as is necessary to cause the inertia weight 109 to bear on the cover plate 102, since the rearward movement of the said weight is in fact retarded by the pallet 113. As mentioned above, the maximum acceleration with rocket projectiles is only reached after about 0.5 to 0.8 second; this slow increase in speed is thus fundamentally different from the sudden acceleration impulse of an impact due to dropping. Thus, when the projectile is dropped on to its base, the inertia weight is only moved back a comparatively short distance and is then brought again by the spring 119 into its forward position (FIGS. 1 and 2). The delay mechanism 110, 111, 112, 113 is adjusted for forward and rearward movement. As described above, the stem 114 of the safety finger is held in the inertia weight 109 for the timing escapement 68 until the return movement of the weight 109 into an intermediate position can still not lead to the locking of the finger 114 on the hairpin spring 115, that is to say, for releasing the balance member 68. Thus, after the shock due to dropping has subsided, all functional parts of the fuze are again in the initial position and all safety devices are fully operative again.

On firing, the inertia weight 109 is forced rearwardly during the acceleration period and, since it is guided rectilinearly on the posts 105 and 106, the engagement of its pin 103 in the worm 107a causes a rotation of the worm member 107, which is slowed down by the time of the delay mechanism 110, 111, 112, 113. The rearward movement of the inertia weight 109 is also counteracted by the thrust spring 119. The time-safety mechanism is so adjusted that the bottom surface of the inertia weight 109 has reached the intermediate plate 102 at the end of the

predetermined safety travel. In this position, the reduced end 114a of the safety finger 114 is also at the height of the hairpin locking spring 115, so that the arms thereof close around 114a and it prevents the safety finger 114, 5 and with it the inertia weight 109, from moving forward again under the action of the thrust spring 119 after the rearward pressure has ceased.

The blocking plate 117 for the needle passage now no longer forms an obstacle for the striker pin 15b, since 10 with the rearward travel of the inertia weight 109, the collar 107b arranged on the rear end of the cylindrical worm element 107 has been rotated to such an extent that its cut-away part 107d (FIGS. 5 and 6) can now move past the locking pin 116 on the locking plate 117, which 15 formerly had rested laterally on the collar 107b (see FIG. 6), so that the passage for the striker pin 15b is freed.

The collar 107b is also of such dimensions in the peripheral direction that the pin 116 is still not freed in intermediate positions of the worm and of the inertia 20 weight.

We claim:

1. Time fuze with sensitive fuzing for projectiles with and without rifling, comprising a striker pin, a cylindrical worm with a spiral groove therein rotatably mounted on the striker pin, an inertia weight provided around the worm to drive the latter, a transverse pin in the weight projecting into and engaging in the groove in the worm, a timing mechanism having a balance regulator mounted in the fuze, means to prevent rotation of the weight, and a safety finger engaging the balance regulator and mounted on the weight parallel to a longitudinal axis of the fuze to secure the balance regulator of the timing mechanism.

2. Time fuze according to claim 1, in which a toothed 35 wheel is provided secured on the cylindrical worm to rotate therewith and in which a pinion and a rocking pallet are provided with the pinion mounted at the forward end of the worm and in cooperative meshing engagement with the toothed wheel to operate the pallet.

3. Time fuze according to claim 1, in which a rocker 40 plate is provided pivotally mounted in a transverse plane in the fuze to one side of the striker pin for shutting off a passage for the striker pin and is mounted beneath the worm and the striker pin to serve as an additional safety 45 device and in which a torsion spring and stop pin are provided mounted on the rocker plate, said plate being held against the torsion spring in a safety closed position by the stop pin which bears externally against a hollow end of the worm, and a wall of the hollow end being 50 formed with a recess therein for the passage of the stop pin on the rocker plate upon completion of the rotation of the worm in the rear dead-centre position of the inertia weight.
